George Guild, Inventor

Richard Bowen
his Attorney

UNITED STATES PATENT OFFICE.

GEORGE GUILD, OF SOUTH HOUSTON, TEXAS.

JACK-BLOCK.

1,143,760.

Specification of Letters Patent. Patented June 22, 1915.

Application filed June 17, 1913, Serial No. 774,222. Renewed November 30, 1914. Serial No. 874,923.

To all whom it may concern:

Be it known that I, GEORGE GUILD, citizen of the United States, residing at South Houston, in the county of Harris and State 5 of Texas, have invented certain new and useful Improvements in Jack-Blocks, of which the following is a specification.

This invention has reference to improvements in jack-blocks used for the purpose of 10 holding the wheel of a car to the rail in jacking up the journal box, to remove, renew or replace the journal bearings or brasses.

The primary object of the invention consists 15 of the provision of a specially constructed stand or base which can be applied to any form of car wheel, upon either side of a car, and which is not dependent upon the relative position of the wheel with respect to the tie, but is held entirely by the 20 wheel and rail.

A further object of the invention resides in the provision of a device of this character 25 which comprises but a few simple parts unlikely to become impaired and which can be readily applied without necessitating the use of any special tools.

The invention consists briefly of a specially 30 constructed block or base, a lifting screw carried by the said base, and means arranged upon the said base for fastening the latter in proper position to the wheel and against the rail.

The above and additional objects are accomplished 35 by such means as are illustrated in their preferred embodiment in the accompanying drawings, described in the following specification and then more particularly pointed out in the claims which are 40 appended hereto and form a part of this application.

In describing my invention in detail reference will be had to the accompanying drawings wherein like characters denote like or 45 corresponding parts throughout the several views, and in which:

Figure 1 is an elevation of a car wheel, illustrating the application of the invention; Fig. 2 is an end view, the rail being shown 50 in section; and Fig. 3 is a detail perspective view of the base or block.

Referring now to the drawings, wherein is illustrated the preferred form of my invention, the numeral 1 designates a car wheel 55 of the ordinary type, 2 the axle upon which

the car wheel is mounted and 3 a journal box of any well known construction.

It is the purpose of this invention to provide means in the nature of a jack-block for lifting the journal box without lifting the 60 wheel of the car thus permitting the bearings or brasses contained therein to be removed, repaired or renewed as occasion demands. To accomplish this result I provide a block or base portion designated in 65 its entirety by the numeral 4, the said base comprising laterally projecting extensions 5 in the extremities of which openings or holes 6 are provided, and through which wheel engaging hook-shaped members 7 extend, the said members overlapping the flange of the wheel and preventing oscillatory movement of the wheel during the jacking up of the journal box. An adjustable nut 8 is arranged over the threaded extremity of each member 7 for drawing the 70 curved or extended portion thereof into firm engagement with the inner face of the car wheel. A depending portion 9 is also formed integrally with the base 4 of the device, this 75 portion likewise having a threaded opening 10 formed therein through which an adjustable exteriorly threaded screw bar 11 extends, one extremity of the said bar engaging the web of the rail upon which the car wheel 80 is resting for supporting the entire base against lateral movement, the adjustment of the said bar 11 being controlled through the medium of a head 12 provided therefor.

The base 4 is further provided with a forward extension 13 likewise formed integrally therewith, the said extension having an interiorly threaded bore 14 extending vertically therethrough, through which the lifting screw 15 of the device extends, the 90 screw having the usual head 16 formed thereupon for engaging the under face of the journal box 3 for elevating the latter independent of the car wheel for removing or repairing the bearings or brasses when occasion demands. To prevent vertical or upward movement of the car wheel during the operation of the elevating screw 15, a flange or projection 17 extends inwardly from the base 4 of the device, the said flange overlapping the annular flange of the car wheel or fitting within the recess ordinarily formed within the outer face of the car wheel, the engagement between the said projection and the said annular flange of the wheel retain- 100 105 110

ing the latter in engagement with the rail upon which it is supported.

In operation, it will be seen that the base 4 is first positioned with the projection 17 5 overlapping the said annular flange of the wheel, whereupon the threaded bar 11 is adjusted to firmly engage the rail in the manner above set forth. After adjusting the bar 11, the extensions of the hook-shaped members 7 are drawn firmly in engagement with the inner face of the car wheel by the operation of the nuts 8, which with the said bar 11 fastens or locks the base to and upon the car wheel and rail upon which the car wheel is 15 supported. The base having been positioned in the above manner the head 16 of the lifting jack is turned and in this manner the journal box 3 is lifted or jacked up to allow the brasses or bearings to be acted upon as 20 desired.

It will be seen from the above, taken in connection with the accompanying drawings that the device is not dependent for support upon the position of the car wheel with 25 respect to the cross tie, as the entire block is supported by its engagement with the wheel itself and the rail; that the wheel is held against lateral, vertical and oscillatory movement by the several elements comprising 30 my invention; and that the block or base when arranged over the wheel and rail in the proper manner effects a rigid support for the lifting screw by means of which the journal box is raised or elevated. 35 It will be understood that the above description and accompanying drawings comprehend only the general and preferred embodiment of my invention and that various minor changes in the details of construction, 40 proportion and arrangement of parts may be made within the scope of the appended claims and without sacrificing any of the advantages of my invention.

Having thus fully described my inven-

tion, what I claim as new and desire to secure by Letters Patent, is:—

1. A car wheel jack-stand including a support member, adjustable means carried by said member and disposed for engagement with the rail upon which the wheel is supported to lock the said member against lateral play, adjustable means carried by said support and disposed for engagement with the periphery of the car wheel to lock the support member against longitudinal play, 55 means adapted for engagement with the wheel to lock the support against vertical play, and means operable upon the support for raising and lowering the journal box of the wheel axle, as and for the purpose set forth.

2. In a car wheel jack-stand, a base support member disposed to extend in parallel relation to the car wheel acted upon, a lateral integrally formed extension, means operable upon said extension for raising and lowering the journal box of the wheel axle, side extensions integral with said base support, a hook-shaped member adjustable upon each extension, the said members being so 70 formed as to overlap and engage the periphery of the wheel in spaced relation to its rail support to prevent oscillatory movement of the said wheel during a jacking operation, a bolt adjustable upon said base support, said bolt being adapted for engagement with the said rail to maintain said base against lateral play, and a tongue integral with the said base and disposed for engagement with the wheel to lock the same 75 against vertical play, as and for the purpose set forth.

In testimony whereof I affix my signature in presence of two witnesses.

GEORGE GUILD.
